[57] CLAIM

The ornamental design for a frame for a windshield wiper for vehicles, as shown and described.

DESCRIPTION

FIG. 1 is a perspective view of the frame for a windshield wiper for vehicles showing my new design;

FIG. 2 is an elevational view thereof showing the side opposite that shown in FIG. 1;

FIG. 3 is an end elevational view looking from the right of FIG. 2, the opposite end being a mirror image thereof;

FIG. 4 is a bottom plan view thereof; and,

FIG. 5 is a perspective view of a frame for a vehicle windshield wiper for vehicles showing a second embodiment of my new design wherein the sole difference resides in the addition of a second aperture in the sidewall of the central area thereof.
